UNITED STATES PATENT OFFICE

LOUIS E. PFEIFFER, OF PHILADELPHIA, PENNSYLVANIA.

APPARATUS FOR GLASS MANUFACTURE.

SPECIFICATION forming part of Letters Patent No. 280,397, dated July 3, 1883.

Application filed November 7, 1882. (No model.)

To all whom it may concern:

Be it known that I, LOUIS E. PFEIFFER, of the city and county of Philadelphia, and State of Pennsylvania, have invented an Improvement in Apparatus for Glass Manufacture, of which the following is a specification.

My invention has reference to glass manufacture; and it consists in providing mechanical means adapted to a glass-furnace to blow up the glass, the said means producing blasts of air, either hot, warm, or cold, and directing the same into suitable channels under the control of the operators, and in details of construction, all of which are fully set forth in the following specification, and shown in the accompanying drawings, which form part thereof.

The object of my invention is to provide suitable mechanical means to take the place of manual labor in glass-blowing—a class of work which is most injurious to the health of the operators.

In the drawings, Figure 1 is a side elevation of my improved glass-blowing apparatus attached to a glass-furnace. Fig. 2 is a sectional elevation of the blow-tube and its connections with the air tubes or pipes, and Fig. 3 is an elevation of a modified form of blow-tube.

A is a glass-furnace of the ordinary construction, and in which B are the usual apertures or doors through which the glass-blower's rod or blow-tube is inserted to extract liquid glass from the crucibles.

C is a circular or bustle pipe, and is adapted to act as a reservoir for the air forced therein by blower E through pipe D. This pipe D may enter directly into reservoir C, or, if desired, it may pass first through the furnace, as shown at D', to heat the air. The reservoir C is further provided with a regulator-valve, C', to govern the pressure of the air, but I do not consider that its use is absolutely necessary.

Projecting down from reservoir C, in front of each door B, are tubes F, to which are secured flexible tubes G, or metal pipes with universal joints at top.

To the lower end of tube G is secured a nozzle, I, provided with a valve, H. The lower part, I', of said nozzle is made tubular and incloses a flexible tube, I'', which is pressed inwardly by springs i, the whole being retained in place by cap J, provided with lugs J', against which

the spring-catches L, attached to the blow pipe or tube K, catch to retain the end or mouth of said blow-tube in the spring-nozzle. The end of the blow-tube which is inserted in the nozzle may be somewhat pointed to allow ready insertion, and its body may be separated by the insertion of a non-conducting medium, K', so as to prevent the part which enters the nozzle from being overheated.

The operation is as follows: The fan or blower being in motion, air, either cold or hot, is forced into the reservoir or main, where it is retained, any excess of pressure being liberated by the regulator. The blow-tube is then inserted into the glass pot or crucible, and after sufficient glass is caught upon the end it is removed, and the other end inserted in the flexible or spring nozzle and locked there. The tube may be moved about as desired. Air is then let into the tube by valve H, its quantity or pressure being controlled by the operator.

I do not limit myself to the exact construction shown, as it may be modified in various ways without departing from my invention.

If desired, the nozzle end of the blow-tube may be made of a non-conducting material—as glass—in place of at K', a short distance below, as in this case one only joint would be required.

Having now described my invention, what I claim as new, and desire to secure by Letters Patent, is—

1. In glass-blowing apparatus, the combination of a glass-blower's tube with mechanical means to create a current of warm air under pressure through said tube, substantially as and for the purpose specified.

2. In glass-blowing apparatus, the combination of a glass-blower's tube with mechanical means to force air under pressure through said tube, and means to automatically control the pressure of said air, substantially as and for the purpose specified.

3. In glass-blowing apparatus, the combination of a glass-blower's tube with mechanical means to force air under pressure through said tube, means to heat the air, and a valve to control the quantity of air allowed to escape through said blow-tube, substantially as and for the purpose specified.

4. In glass-blowing apparatus, the combi-

nation of an air-blower, an air-main, a safety-valve in said main, glass-blowers' tubes, and flexible tubes connecting said main with said blow-tubes, substantially as and for the purpose specified.

5. In glass-blowing apparatus, the combination of an air-blower, an air-main, a safety-valve in said main, glass-blowers' tubes, flexible tubes or pipes connecting said main with said blow-tubes, a nozzle to detachably receive the end of the said blow-tubes, and means to regulate and control the passage of air through said tubes, substantially as and for the purpose specified.

15. 6. The combination of an air-main with a flexible pipe leading therefrom, a nozzle upon the end of said pipe, a glass-blower's tube

adapted to fit into said nozzle, and a catch to hold said nozzle and blow-tube together, substantially as and for the purpose specified.

7. The combination of air-pipe G, valve H, nozzle I, provided with flexible tube I², and springs i, with blow-tube K, substantially as and for the purpose specified.

8. A glass-blower's tube made of metal, and provided with a top part made of a non-conductor to heat, substantially as set forth.

In testimony of which invention I hereunto set my hand.

LOUIS E. PFEIFFER.
